UNITED STATES PATENT OFFICE.

WILLIAM H. INSLEY, OF INDIANAPOLIS, INDIANA, ASSIGNOR TO INSLEY MANUFACTURING COMPANY, OF INDIANAPOLIS, INDIANA, A CORPORATION OF INDIANA.

EXCAVATOR OF THE SCRAPER TYPE.

Application filed September 24, 1923. Serial No. 664,405.

To all whom it may concern:

Be it known that I, WILLIAM H. INSLEY, a citizen of the United States, residing at Indianapolis, in the county of Marion and 5 State of Indiana, have invented a new and useful Improvement in Excavators of the Scraper Type, of which the following is a specification.

The object of my invention is to produce 10 an excavator of the scraper type, embodying a scraping excavator bucket supported upon a carriage movable upon a track which may be a cable capable of being slackened and tautened, in which the contents of the 15 bucket may be transported and dumped, at any desired point, from the rear end of the bucket, by a continuing forward pull upon the dragline.

The accompanying drawings illustrate 20 my invention. Fig. 1 is a side elevation of an apparatus embodying my invention, wherein the dumping takes place through the rear portion of the bottom of the bucket; Fig. 2, a plan of the apparatus shown 25 in Fig. 1; Fig. 3, a partial vertical section showing the device illustrated in Fig. 1, in dumping position; Fig. 4, a view in partial vertical section of another embodiment of my invention, arranged for rear end dump; 30 Fig. 5, a view similar to Fig. 4 with the parts in dumping position; Fig. 6, an end elevation of the structure shown in Figs. 4 and 5.

In the drawings, 10 indicates a suitable 35 supporting track which, in the present instance, is a slack-line cable supported in the usual manner, i. e., at one end to a suitable "dead man," and at the other end to an appropriate block and tackle supported from 40 the top of a tower, and adapted to be tautened and loosened. The manner of supporting the track cable 10 is well known in the art and therefore not illustrated in the present application. Slidably mounted on the 45 track 10 is a carriage 11 provided, below the track 10, with a pair of supports 12-12, preferably idler wheels. Suspended from the rear end of carriage 11, at 13, is a suspension chain 14, the lower end of which is 50 attached to the rear end of a scraper bucket 15. Pivoted to carriage 11, preferably near its forward end, are two arms 16-16, between the forward ends of which is mounted a roller 17 arranged to ride upon track 55 10 and also to ride up on a block 18 which

may be secured to track 10 at any desired point in its length where dumping is to occur.

Suspended from the forward ends of arms 16 are suspension chains 19-19, the lower 60 ends of which are connected to the upper forward corners of bucket 15.

Mounted upon bucket 15 at its top, and preferably at an intermediate point in its 65 length, is an idler 20.

In the form shown in Figs. 1, 2 and 3, the bucket is provided with a fixed rear wall 21 and with a fixed bottom 22 which extends from the front edge rearwardly toward but not to the rear wall 21. The gap 70 between the rear edge of bottom 22 and the lower edge of end wall 21 may be closed by a swinging door or bottom section 23. Attached to the bottom section 23 are two upwardly converging chains 24 connected at 75 their upper ends to a connector 25 which is carried by the lower end of a chain or cable 26 passed upwardly and forwardly over idlers 12, thence downwardly and forwardly around idler 20 and thence upwardly and 80 forwardly to the point of attachment 27 to carriage 11, the arrangement being such that, when wheel 17 rests upon track 10 the bucket 15 will occupy, by gravity, such a position that door 23 will be held in closed position. 85

Translatory movement of carriage 11 along track 10 may be obtained in any desired manner by which a digging or scraping action of the bucket may be obtained, the more convenient means for accomplishing this purpose being a dragline 30, upon 90 which a pull may be exerted; a bridle 31 extending from the free end of the dragline to the bucket near its forward lower corners; and a line 32 extending from the free end of the dragline to the forward end of the carriage 11.

In operation, the bucket being allowed to rest upon the ground where excavation is to be accomplished, door 23 will be held closed 100 by the weight of the bucket and a drag exerted upon the bucket will cause it to become filled. The track cable 10 will then be tautened and the load will be lifted, the cable 26 being held taut by the weight of the loaded bucket and the door 23 thus held closed and the load retained in the bucket. 105

When block 18 is reached, wheel 17 will ride up on said block and will thus lift the forward end of the bucket to the position 110

shown in Fig. 3, said movement causing wheel 20 to move upwardly and thus provide slack in cable 26 which will permit door 23 to open under the weight of the load and permit the load to be discharged.

The operator may cause the carriage 11 to approach block 18 slowly so that the upward movement of wheel 17 on said block will be slow and consequently the provision of slack in cable 26 may be as slow or as rapid as desired, and the dumping of the load may be thus controlled.

The construction shown in Figs. 4, 5 and 6 is, in most particulars, the same as the construction previously described. In this form, however, the bucket is provided with an end wall having a swinging door 40 as its lower portion, said door being normally held closed by means of cables 41, attached 20 to the door and to the cable 26, each cable 41 being passed around an idler 42 mounted in a casing 43 arranged in a rear corner of the bucket.

In operation, this form of the invention is 25 practically the same as the form previously described, the only difference being that the discharge of the load is through the rear end wall of the bucket instead of through the bottom near its rear end.

30 I claim as my invention:

1. A scraper excavator comprising a carriage, a scraper bucket, having a load-retaining door adjacent its rear end, a suspension connection between the rear end of the bucket and the carriage, a member carried by the carriage and laterally movable relative thereto, a connection between said member and the front end of the bucket whereby a lateral movement in one direction will lift the front end of the bucket, and means carried by the carriage and associated with the bucket, and connected with the door, whereby the door will be held closed by said means when the front end of the bucket is in its lower position.

2. A scraper excavator comprising a carriage, a scraper bucket, having a load-retaining door adjacent its rear end, a suspension connection between the rear end of the bucket and the carriage, a member carried by the carriage and laterally movable relative thereto, a connection between said member and the front end of the bucket whereby a lateral movement in one direction will lift the front end of the bucket, a cable attached at one end to the carriage and at the other end to the bucket door, and at intermediate points passed over supports on the bucket and on the carriage, whereby the position of the bucket relative to the carriage will control the door.

3. The combination with a slack-line track, of a carriage slidably mounted thereon, a laterally movable element carried by the carriage, a block mounted on the track cable and engageable by said laterally movable element to cause lateral movement thereof upon movement of the carriage toward the block, a scraper bucket suspended from the carriage and from the laterally movable element, a door forming a part of the load-retaining portion of the bucket, means connected with the carriage and door and associated with the bucket, for controlling the position of the door by relative movement between the bucket and carriage, and a dragline connected to the bucket and to the carriage.

4. The combination with a slack-line track, of a carriage slidably mounted thereon, a laterally movable element carried by the carriage, a block mounted on the track cable and engageable by said laterally movable element to cause lateral movement thereof upon movement of the carriage toward the block, a scraper bucket suspended from the carriage and from the laterally movable element, a door forming a part of the load-retaining portion of the bucket, a cable connected at one end to the carriage and at the other end to the door and at intermediate points associated with portions of the bucket and carriage whereby the door will be controlled by relative movement between the bucket and carriage, and a dragline connected to the bucket and to the carriage.

5. A scraper excavator comprising a carriage, a laterally movable element carried by the carriage, a scraper bucket suspended at one point from the carriage and at another point from the laterally movable element, a load-engaged door forming part of said bucket, and means for controlling the position of said door by movement of the laterally movable element.

6. A scraper excavator comprising a carriage, a laterally movable element carried by the carriage, a scraper bucket suspended at one point from the carriage and at another point from the laterally movable element, a load-engaged door forming part of said bucket, a cable connected at its opposite ends to the carriage and to the bucket door, and passed at intermediate points over portions of the bucket and carriage.

In witness whereof, I, WILLIAM H. INSLEY, have hereunto set my hand at Indianapolis, Indiana, this 20th day of September, A. D. one thousand nine hundred and twenty-three.

WILLIAM H. INSLEY.
